[57] CLAIM

The ornamental design for a refuse container, substantially as shown and described.

DESCRIPTION

FIG. 1 is a perspective view of a refuse container showing my new design;

FIG. 2 is a perspective view thereof showing the side and end opposite to that in FIG. 1;

FIG. 3 is a perspective view of a refuse container showing a second embodiment of my new design; and

FIG. 4 is a perspective view thereof showing the side and end opposite to that in FIG. 3.

FIG. 1

FIG. 2

FIG. 3

FIG. 4
